UNITED STATES PATENT OFFICE.

ALBERT LEWIS, OF MARSHALLTOWN, IOWA.

POWER-TRANSMITTER.

SPECIFICATION forming part of Letters Patent No. 466,352, dated January 5, 1892.

Application filed October 10, 1891. Serial No. 408,310. (No model.)

To all whom it may concern:

Be it known that I, ALBERT LEWIS, a citizen of the United States, residing at Marshalltown, in the county of Marshall and State 5 of Iowa, have invented a new and useful Power-Transmitter, of which the following is a specification.

My invention relates to power-transmitters, and more especially to that class of devices 10 used in connection with windmills; but it is also designed to be used in connection with any machine or mechanical movement in which it is desired to convert rotary into reciprocating motion; and the invention has for 15 its object to provide a power-transmitter which will be simple in construction and effective in operation to attain its main object to accomplish an increased length of stroke for the actuating-pitman.

20 With these and other objects in view, which will be readily apparent as the nature of the device is better understood, the invention consists in the novel mechanical movement hereinafter more fully described, illustrated in 25 the accompanying drawings, and specifically pointed out in the appended claims.

In the accompanying drawings, Figure 1 is an inner elevation of the upper portion of a windmill, the tower and supports not shown. 30 Fig. 2 is a detail in perspective of the upper portion of the windmill-casting provided with a power-transmitter constructed in accordance with my invention. Fig. 3 is a similar view of the toothed pitman. Fig. 4 is a similar view of a modification.

A represents the upper portion of an ordinary tubular casting usually employed with vertical wind-wheels, and is provided at its extreme upper limit with the brackets or arms 40 B, by which the same is supported within and upon the ordinary windmill-tower, which, being of the usual type, is not illustrated in the drawings, and said casting is also provided with the upper horizontal bearing C, within 45 which is journaled the wind-wheel shaft D, carrying upon its outer end an ordinary vertical wind-wheel E, while upon its inner end is mounted the circular plate or disk F, which is ordinarily employed as the crank-plate, with 50 which the pitman is connected with the pump-rod. Upon the outer face of said plate or disk and also carried by the wheel-shaft D is the

pinion G, provided with the central projection or arm g, upon which is journaled the friction-wheel g', the function of which will 55 be presently described.

The power-transmitting pitman H is pivotally secured at its lower end to the sliding block h, traveling in the vertical slot I at the upper end of the tubular casting and connected to the upper end of the pump-rod J, inclosed within said casting and connected with the pump or other device to be operated in the usual manner.

The upper end of the pitman-rod H terminates in an enlarged head K, which is provided with an oblong slot k', having curved ends k², and having an inner toothed surface k³, that is designed to be engaged by the pinion G, carried upon the inner end of the wheel-shaft. The side of the enlarged head K adjacent to the plate or disk F is provided with an encircling flange k⁴, projecting inwardly and beyond the edges of the teeth, and which is designed to take between said pinion and the plate or disk F as the pinion travels around the toothed surface or edges of said pitman-head, thus serving to hold the head in position upon the face of said plate or disk and the pinion G in mesh therewith. Extending 60 longitudinally over the slot in the pitman-head and raised above the plane thereof is the guide-bar L, provided with the inwardly-projecting guide-rib l, that extends inwardly a sufficient distance and is of such length as 65 to permit the friction-roller g', carried by the pinion G, to travel upon both sides of the same and over each end thereof as the wheel-shaft carries said pinion up and down each side of the toothed surface of said slot to 70 cause a reciprocation of the pitman-arm.

It can be readily seen from the foregoing that as the wheel-shaft D revolves the pinion G, meshing with the teeth in the oblong slot, will be held into engagement upon one 75 side thereof as the same is either traveling in an upward or downward direction by said guide-rib engaging the friction-roller g' and firmly holding the pinion and toothed surface in mesh, and that after the pinion 80 has traveled the entire length of the slot upon one side that when it reaches either curved end of the same the roller will clear the end of the guide-rib and pass over and against 85 90 95 100

the opposite side of the same to hold the pinion in mesh with the teeth upon the opposite side of said slot, thus giving the pitman a longer stroke than is usual in devices of this character. The same result is accomplished by a slight modification, as illustrated in Fig. 4 of the drawings. In this construction, instead of having the inner surface of the oblong slot toothed, as described, the same has a smooth bearing-surface, which forms a guide for the roller N, which supplants the pinion, while the friction-roller g' is dispensed with and a small pinion O is used in lieu thereof and is designed to engage the toothed sides P of the rib l previously described. It can be seen that this modification, which is of but slightly-different construction, still retains the principles of my invention and accomplishes the same result in practically the same manner without departing from the spirit thereof.

Having thus described my invention, what I claim, and desire to secure by Letters Patent, is—

1. In a power-transmitter, the combination, with a rotary shaft having a circular flange or disk upon one end, of the pinion carried by said shaft upon the face of said disk and provided with a central projection carrying a friction-roller, the pitman-arm having an oblong slotted head at one end, having an inner toothed surface and working over the face

of said flange or disk, and a guide-rib secured longitudinally of said slot and adapted to engage the friction-roller of said pinion and hold the same alternately in mesh with the opposite toothed sides of said slot, substantially as set forth.

2. In a power-transmitter, the combination, with a rotary shaft having a circular flange or disk upon one end, of the pinion carried by said shaft upon the face of said disk and provided with a central projection carrying a friction-roller, the pitman-arm having an oblong slotted head at one end, said slot being provided with curved ends and an inner toothed surface, an inwardly-projecting and encircling flange adapted to take between said pinion and said disk, and a guide-bar secured longitudinally of said slot and provided with the inwardly-projecting guide-rib projecting within said slot and adapted to engage said friction-roller and hold said pinion in mesh with the opposite toothed sides and ends of said slot, substantially as set forth.

In testimony that I claim the foregoing as my own I have hereto affixed my signature in the presence of two witnesses.

ALBERT LEWIS.
